UNITED STATES PATENT OFFICE.

ORLANDO SHEPPARD, JR., OF ATLANTA, GEORGIA.

MILL PLATE.

Application filed February 1, 1924. Serial No. 690,005.

The present invention provides improvements in grinding mills, these improvements being applicable generally to mills of the kinds employing opposed relatively revolute grinding plates between the faces of which the material is ground or reduced.

A primary object of the invention is to provide novel and improved grinding plates for attrition mills of the type employing plates having ribs and pockets in their faces between which the material is ground or reduced. Heretofore it has been proposed to provide the faces of the plates with ribs, some of which extended radially of the axis of the plate and other ribs which extended in a direction generally circumferentially of the plates, pockets being formed between the ribs, but in the ribbed constructions previously proposed, the circumferential 20 ribs of the opposed plates either produced no grinding action between them or such grinding action as may have been produced between the circumferential ribs occurred only through portions of the relative rotation of the plates, and hence the capacity of the mill was limited either wholly or largely to the grinding action which occurred between the radial ribs, and furthermore, in such previously proposed constructions, the 30 radial ribs became worn rapidly and also unevenly, thus prematurely rendering the plates unfit for further use. The present invention provides grinding plates for mills of this type wherein the ribs which extend 35 in a direction generally circumferentially of the plates are so arranged that they cooperate at all times during the operation or throughout the relative rotation of the plates to produce between them a shearing 40 or grinding action upon the interposed material in course of reduction, these ribs thus co-acting with the radial ribs to afford the maximum grinding efficiency and capacity for a mill of given size, and, furthermore, 45 the wear will be distributed uniformly between the radial and circumferential ribs, so that the period of usefulness of the plates is greatly extended. Moreover, the present invention provides a rib construction which 50 presents two sets of grinding edges, one of which sets can be brought into use after the other set has become worn or their efficiency has become impaired, it provides plates which may be made in sections which 55 are identical, and hence of equal weight, so that the assembled plates will be inherently

balanced, thus obviating the necessity of providing balance-weights or other balancing means for the plates, and it also provides other improvements in the grinding plates which increase the efficiency of the mill and obviate objections found to exist in attrition mill plates as heretofore proposed.

Another object of the invention is to provide a reinforced structure for the grinding plates or members of attrition mills, disk hullers and similar mills where the grinding plates or members revolve at relatively high speeds. Heretofore, it has been usual to make the grinding plates of relatively soft steel or other cast metal, in order to reduce the liability of the plates to fly apart under centrifugal force and thereby damage or wreck the mill, when the plates become cracked or broken, due to the entrance of a piece of metal or other foreign substance between the plates, or to other causes, but in constructing the plates of relatively soft metal in order to minimize the damage referred to, the durability of the plates is accordingly reduced. The present invention provides a reinforced structure for such plates whereby the plates may be made of relatively hard cast steel or metal which will afford greatly increased durability and wearing properties for the plates, and the reinforcement will prevent flying apart of the plates, should they become cracked or broken, and, moreover, the reinforcement will retain the broken parts of the plates in proper position so that the use of the plates can be safely continued until they have served their usual period of usefulness.

To these and other ends, the invention consists in certain improvements and combinations and arrangements of parts, all as will be hereinafter more fully described, the features of novelty being pointed out particularly in the claims at the end of the specification.

In the accompanying drawing:—

Figure 1 is a face view of an attrition mill plate constructed in accordance with the preferred embodiment of the invention;

Figure 2 is a view showing sections of two attrition mill plates constructed as shown in Figure 1 and arranged in opposed relation, this view showing a portion of one of the plates in section in a plane parallel to its working face and showing a portion of the other plate in face view;

Figure 3 represents, on an enlarged scale,

a section taken radially through a pair of attrition mill plates and their supporting disks constructed as shown in Figures 1 and 2;

5 Figure 4 represents, on an enlarged scale, a section taken radially through one of the plates constructed as illustrated in Figures 1 to 3, inclusive;

10 Figure 5 is a detail view of a reinforcement provided by the present invention and applicable to attrition plates and also to the plates of disk hullers and other mills, the dot-and-dash line outlining a portion of the mill plate in which the reinforcement is 15 adapted to be embedded;

Figure 6 represents a section on the line 6—6 of Figure 5 illustrating the manner in which the reinforcement is embedded in the mill plate; and

20 Figure 7 is a diagrammatic view illustrating the preferred mode of generating or laying out the substantially circumferential ribs of the improved plates.

Similar parts are designated by the same 25 reference characters in the several views.

The preferred embodiment of the invention is shown in the accompanying drawings and will be hereinafter described in detail. It is to be understood, however, that the 30 invention is not restricted to the particular construction shown, as equivalent constructions are contemplated and such will be included within the scope of the claims.

In the present instance, 1 designates the 35 disks such as those commonly used in attrition mills, these disks being mounted respectively on shafts 2 which may be driven in relatively reverse directions in the usual way, the material to be ground or reduced being 40 fed in the usual way between the disks and the material feeding outwardly or toward the peripheries of the disks under centrifugal force, the material while passing outwardly being ground or reduced between the 45 opposed faces of the plates 3, the latter being preferably fitted into recesses 4 formed in the outer marginal portions of the disks and secured therein by a suitable number and arrangement of bolts 5. The plates 3 in the 50 opposed disks are preferably of duplicate construction, their working faces having a duplicate arrangement of grinding ribs thereon, and each plate is preferably constructed from a number of sections 3^a, the 55 different sections of each plate being preferably of duplicate construction having the same arrangement of shearing or grinding ribs thereon.

The present invention provides a grinding plate for attrition mills which has a novel 60 and improved construction and arrangement of shearing or grinding ribs on its working face, some of these ribs extending radially of the plate and other ribs extending generally circumferentially on the face of the

plate but having a pitch toward the outer edge of the plate, whereby a continuous shearing or grinding action will be produced between the circumferentially extending ribs of the opposed plates and between the circumferential ribs of each plate and the radial ribs of the opposed plate, as well as between the radial ribs of the opposed plates, throughout the relative rotation of the plates, in consequence of which 75

maximum grinding efficiency and capacity are obtained, the wear taking place is distributed uniformly between the circumferential and radial ribs, and other advantages are secured over attrition mill plates as 80

previously proposed. Preferably and as shown in the present instance, the working face of each plate section 3^a is formed with an outer peripheral rib 6 which is concentric with the axis of the plate or the disk 85

on which it is mounted, and the working face of each plate section is provided with a suitable number of ribs 7 which extend in a direction generally circumferentially of the plate but with a pitch toward the outer 90

edge of the plate, and with intervening or connecting ribs 8, which latter extend radially of the plate, pockets or depressions 9 being formed between the radial ribs and the ribs 7 and between the radial ribs and the outer 95

rib 7 and peripheral concentric rib 6. The ribs 7, according to the present invention are so located and arranged on each plate section that the plate made up of these 100 sections will present these ribs 7 to corresponding ribs on the opposed plate in such a manner that rotation of the opposed plates in reverse directions will produce continuous or uninterrupted shearing or

grinding action of these ribs 7 on the material undergoing reduction throughout the complete rotation or revolution of the plates; and preferably the ribs 7 of each plate section join with or form continuations of the 105 corresponding ribs of the adjacent plate sections. To obtain these results, the ribs 7 preferably extend on arcs of circles, the centers of which are offset relatively to the center of revolution of the plate. Figure 110

7 illustrates diagrammatically one mode of generating the circumferential ribs 7. In this diagram O is the center of the inner and outer circles a and b, while o' and o² are centers about which are described the lines 7^a and 7^b respectively, which lie below and 115

above the line or diameter A—B. By appropriately locating the centers o' and o², the arcs 7^a which lie below the line A—B will join the arcs 7^b which lie above the line 120

A—B. Two diagrams conforming with that shown in Figure 7, if reversed and superposed, would present the lines 7^a and 7^b of the opposed diagrams in such manner that they will not coincide at any point in 125

their circumferences or at any point when 130

relatively rotated, but such lines will always intersect one another at a number of points around the circumferences of the diagrams as the latter are relatively rotated, and if 5 grinding plates were made having circumferential ribs arranged thereon in accordance with the lines 7^a and 7^b of this diagram continuous grinding action would be produced between such circumferential ribs. 10 However, it is desirable in practice to construct each grinding plate of a number of sections and it is also desirable that all sections of the grinding plate be of identical construction in order not only to facilitate 15 manufacture and maintenance by the use of a single pattern and interchangeable plate sections, but also to obtain inherent balance in the plate. It will be found that if the diagram is intersected by the lines or dia- 20 meters x—x and y—y so that these lines, together with the line A—B divide the diagram into six segments of equal circumferential length, the lines 7^a and 7^b of one diagram, when superposed upon a duplicate 25 diagram, will intersect on the lines A—B, x—x and y—y, and hence any one of the duplicate segments of the diagram lying between the lines A—B and x—x, x—x and y—y, or y—y and A—B may be taken as a 30 pattern for a set of plate sections, and a plate made up of such sections would embody circumferential ribs which would produce continuous shearing action throughout the revolution of the opposed plates, and, moreover, 35 the circumferential ribs of any section of the plate would be continuous with the corresponding circumferential ribs of adjacent sections. Preferably and as shown in the present instance, one of the duplicate segments of the diagram lying between the 40 line x—x and A—B is substantially adopted as a pattern for the circumferential ribs 7 of the plate section, each of these segments constituting one-sixth of the circumference 45 of the diagram and accordingly the plate is constructed of six sections which will be of identical circumferential rib formation. In the particular construction shown, c is the approximate center of the circumferential ribs of each of the respective plate sections as these ribs are shown in Fig. 2, 50 it being understood that the centers of the circumferential ribs of each plate section are nearly or substantially coincident, and 55 that the centers of the ribs of the different plate sections are located in eccentric relation to, and are spaced eccentrically around, the center O' about which the plate revolves. Each of these circumferential ribs 60 is preferably an arc of a true circle with its center so located that each of such ribs extends from a point within the periphery of the plate section outwardly toward the periphery thereof and so that each con- 65 tinuous circumferential rib of the plate ex- tends from the inner edge of the working face of the plate continuously through the different sections to the peripheral portion of the plate, the ends of the circumferential ribs of any one section alining with or forming continuations of the corresponding ribs of the adjacent plate sections. Of course, there will be six sets of these rib centers located around the center O', in the construction herein shown, to conform with the 70 use of six circumferentially extending but outwardly-pitched ribs. It will be understood, however, that any equivalent arrangement of the circumferential ribs which will produce continuous grinding action upon the material between the plates throughout their revolution may be used, although it is also desirable that the circumferential ribs of one plate section should be continuous with those of the adjacent plate section in order to avoid undue wear or grooving of the radial ribs and which would occur if the circumferential ribs of the plate sections were not continuous. It will also be understood that the number of sections 80 constituting each complete circular plate may vary according to the size or style of the mill, in which cases the number and location of the centers of the circumferential ribs around the center of revolution of 85 the plate will vary accordingly. 90 Preferably and as shown in the present instance, the inner and outer walls of each circumferential rib are substantially perpendicular to the plane of the working face 100 of the plate to provide efficient cutting edges on the inner and outer sides of each of these ribs, so that when one edge of the circumferential ribs of each plate has become worn, the mill disks carrying the plates 105 may be reversed and the operation of the mill then be continued, bringing the outer edges of the circumferential ribs of the opposed plates into operation. In this way, 110 greatly increased serviceability of the grinding plates is obtained. In order to facilitate the passage of the material undergoing reduction between the working faces of the plates and also to avoid banking or packing of the material against the inner walls 115 of the circumferential ribs and thereby disturbing the balance of the plates, a fillet 7^c is preferably formed at the inner side of each circumferential rib between its face and the body of the plate, but this fillet 120 terminates short of the working face of the rib, thus leaving an efficient cutting edge at the inner side of the rib, similar to the cutting edge at the outer side of such rib. The sides of the radial ribs 8, as shown, are 125 preferably substantially perpendicular to the plane of the working face of the plate, so that these ribs present efficient cutting edges at both sides thereof. The circumferential ribs 7 and the radial ribs 8 preferably 130

have working faces of the same width so that they will sustain wear uniformly and thus preserve the faces of the plates in efficient condition throughout their period of usefulness.

The working faces of the radial and circumferential ribs of the opposed plates are preferably parallel from the line L—L outwardly to the periphery of the plates for 10 finish grinding of the material undergoing reduction, but the working faces of the ribs from the inner edges of the plates outwardly to the line L—L are preferably beveled slightly so that they converge as they approach the line L—L, this bevel of the working faces of the ribs facilitating the feeding of the material between the plates and thus promoting the grinding action. The inner edge of each plate is also preferably formed 20 with a beveled feeding surface 10 and a suitable number of breaker ribs 11 are preferably provided which project forward from the feeding surface 10, these breaker ribs serving to break up the material which 25 may be fed to the plates in the form of cakes or lumps, thereby facilitating the entrance of the material between the working faces of the plates.

In using a pair of plates each constructed 30 substantially as hereinbefore described, the plates, when placed opposite to one another will present the ribs 7 to one another in such relation that they will always intersect at a number of points throughout the relative 35 rotation of the plates, the ribs 7 avoiding coincident superposition at any point, and in the operation of this mill, during which the plates are relatively rotated, it being usual to revolve both plates but in opposite 40 directions, the ribs 7 of the opposed plates will produce and maintain a continuous shearing action between them and also between these ribs 7 of each plate and the radial ribs 8 of the opposed plates, Figure 2 45 showing clearly the shearing relation between the ribs 7 of the opposed plates. In consequence, maximum grinding efficiency and capacity are attained and the wear of the plates is distributed uniformly between 50 the circular or circumferential ribs 7 and the radial ribs 8 so that the working faces of the plates are maintained in efficient working condition for a maximum period of time.

The present invention also provides means 55 for reinforcing attrition mill plates and also the plates of disk hullers or other mills which are subjected to centrifugal and other strains while in operation and which, if broken in consequence of the entrance of a 60 foreign body between the plates, or from other causes, would fly apart and damage or wreck the mill or the entire set of plate sections in the mill. Heretofore, the strength and durability of grinding plates have depended upon the kind or quality of raw ma-

terial from which they were made and the method by which this raw material was prepared, it having been the practice heretofore to attempt to construct grinding plates of a certain quality of steel which, if too soft, would rapidly wear out, thus shortening their period of usefulness, and if hard enough to sustain wear for a longer period would be brittle, and hence subject to breakage and destruction. Difficulties in obtaining castings of uniform quality of hardness have resulted in the production of mill plates, some of which were too soft to sustain wear for a sufficient period of time and others were too hard and hence were subject to breakage and destruction.

The present invention provides a reinforcement adapted to be embodied in a mill plate or the sections thereof and capable of greatly strengthening the same so that it will greatly resist breakage and if breakage of the plate or plate section should occur, the reinforcement will serve to retain the fragments or broken parts of the plate or plate section in proper position, thus not only avoiding damage to or destruction of the mill, but also enabling the operation of the mill to continue until the plates have served their usual period of usefulness.

In the present instance, a reinforcement is shown which is suitable for use in attrition mill and disk huller plates, the reinforcement comprising a mesh composed of a suitable number and arrangement of bars 12 and 13 of tough steel or other suitable material capable of withstanding breakage, either or both of these rods at their intersections being preferably offset, as at 14, to produce a fastening or interlocking engagement between them. This mesh is embedded in the mill plate or mill plate section by casting the steel or metal composing the plate around the reinforcement, so that the reinforcement lies in a plane about midway of the thickness of the plate and in the plane of rotation thereof. Preferably and as shown in the present instance, the rod 13 in the middle of the plate section extends radially thereto and the other rods 13 are suitably spaced in parallelism with the middle rod, 115 these rods adjacent to the plate-securing bolts 5 being preferably spaced more closely than at other parts of the plate section in order to secure greater reinforcement of the plate section in the regions of the securing 120 bolts. The reinforcement bars 12, as shown in the present instance, intersect the bars 13 at or substantially at right angles and they are suitably spaced between the inner and outer edges of the plate section.

In using a reinforcement substantially as herein shown and described, the grinding plate may be composed of a steel or material much harder than it has heretofore been possible to use with safety, so that the grind-

ing plate will possess wear-resisting properties to a high degree, and hence the usefulness of the plate will be greatly prolonged. The reinforcement which is enveloped by 5 the steel or material composing the grinding plate and is intimately united therewith, greatly strengthens the plate so that it is capable of resisting, to a high degree, forces tending to crack or break it, and if the plate 10 should become broken, the reinforcement will hold the fragments or parts of the plate or plate section in proper position, thereby not only avoiding damage to the mill, but also enabling the operation of the mill to 15 continue, using the broken plate or plate section until the plate has served its usual period of usefulness.

The preferred form of ribs on the working faces of the plates has been heretofore 20 described whereby continuous shearing action on the material undergoing reduction will be produced, throughout the relative revolution of the plates, between the generally circumferentially extending outwardly-pitched ribs of the opposed plates, and between the generally circumferentially extending ribs of each plate and the radial ribs of the cooperating plate, as well as between the radial ribs of the opposed plates, 25 thereby securing the advantages of greater grinding efficiency and increased capacity for a mill of given size, but it is to be understood that other or equivalent rib formations may be used to obtain substantially the 30 same results. It is preferable, however, to form the generally circumferentially extending ribs as arcs of true circles having a pitch from the inner toward the outer edge of the plates, substantially as herein shown, 35 and to construct each plate of a plurality of identical segmental sections so that the ends of the circumferentially extending ribs of any section align or are continuous with the circumferential ribs of adjacent sections, 40 the manufacture of the plates being thus facilitated, the plates being inherently balanced, and undue wear or grooving of the radial ribs being avoided. It is also preferable to form the circumferentially extending 45 outwardly-pitched ribs with right-angled or efficiently-shaped inner and outer cutting edges whereby the period of usefulness of the plates may be increased by reversing the mill disks carrying the plates, 50 after one pair of the cutting edges provided by these ribs has become worn, thus bringing the other set of cutting edges into operation. The fillets at the inner sides of the circumferentially extending ribs are preferably used as they facilitate the outward 55 feed of the material undergoing reduction and they also avoid banking of the material against the inner sides of these ribs and which, if allowed to occur, would unbalance 60 the plates.

Preferably, and as shown in the present instance, one of the circumferential ribs commences on each of the plate sections, these ribs extending around the face of the plate so that the portions of these ribs borne 70 by each plate section are aligned. By this arrangement, each plate section will have an identical circumferential rib formation thereon, so that one pattern will serve for all of the sections and the sections will be 75 inherently balanced, the number of circumferential ribs corresponding with the number of plate sections used, and each circumferential rib will be overlapped circumferentially by portions of other ribs. In the 80 particular construction shown, the circumferential ribs are also located symmetrical- 85 ly on the working face of the plate, the centers of these ribs being located eccentrically of and spaced symmetrically around the axis of rotation of the plate, and hence the different circumferential ribs will start at points spaced symmetrically around the inner portion of the working face of the plate and will terminate at points spaced 90 symmetrically around the outer portion of such face. Of course, the circumferential ribs not only perform the shearing or grinding function herein described, but they may also function to retard or control the outward feed of the material undergoing reduction between the working faces of the opposed plates as they present ledges against which the material lodges temporarily as it is forced outwardly under the influence of 95 centrifugal force, they thus insuring uniform and complete reduction of the material prior to its final discharge at the periphery of the plates.

The reinforcement provided by the present invention enables the grinding plates of mills of various types or kinds to be constructed of harder material and of greater wear-resisting properties than it has been heretofore safe to use, for notwithstanding the liability of breakage of such plates, due to the increased hardness of the material composing them, the reinforcement not only resists forces tending to break the plates, but should any section of either 105 plate become broken, its parts will be held together and in proper working position, so that the operation of the mill may be safely continued, the broken plate section operating substantially as if unbroken. The preferred 110 form of the reinforcement as applied to attrition mill plates is herein shown and described, but it is to be understood that the reinforcement may take other forms in applying it to the grinding plates of attrition 115 mills, disk hullers or to the grinding plates of mills of other types. Obviously, if the mill plate to which the reinforcement is applied is constructed in one piece instead of in segments, the form of the rein- 120

forcement may be varied to conform therewith.

I claim as my invention:—

1. A grinding plate for mills having a working face provided with a set of projecting ribs which extend circumferentially of the plate, the inner side of each rib having a portion extending substantially perpendicularly to and forming a cutting edge 10 with the face of the rib, and a fillet joining the face of the plate with said portion of the inner side of the rib at a point removed from said cutting edge.
2. A reversible grinding plate for mills 15 having a working face provided with a set of projecting ribs which extend circumferentially and are pitched outwardly from points toward the inner side to points toward the outer periphery of the plate, the inner side of each rib having a portion extending at an angle to the face of the plate to form a cutting edge with the face of the rib, and a fillet joining the face of the plate with said portion of the inner side of the 25 rib at a point removed from said cutting edge.
3. A grinding plate for mills comprising a body of hard cast steel having a dressed working face and a strain-sustaining reinforcement of tough steel embedded in the body behind said dressed face and intimately united therewith and capable of maintaining fragments, broken from the plate, in working position.
4. A grinding plate for mills comprising a body of hard cast steel having a dressed working face and a tough steel rod reinforcement embedded in the body behind said dressed face and intimately united therewith and operative to maintain fragments, broken from the plate, in working position.
5. A grinding plate comprising a body composed of hard cast steel having a dressed working face and a strain-sustaining reinforcement composed of tough steel embedded in the body in a plane behind its working face, said reinforcement being intimately united with the hard cast steel composing the body and operative to maintain frag-

ments, broken from the plate, in working 50 position.

6. A grinding plate comprising a body of hard cast steel having a dressed working face and an intersecting rod reinforcement composed of tough steel embedded in said body and intimately united therewith, said reinforcement constituting a strain-sustaining structure capable of maintaining fragments of a broken plate in working position.

7. A grinding plate comprising a body of hard cast steel having a dressed working face and a tough steel reinforcement embedded in the body behind said dressed face and intimately united therewith, said reinforcement embodying sets of intersecting members, the members of one set being recessed to engage and interlock with the members of the other set, the reinforcement being operative to maintain fragments, broken from the plate, in working position.

8. A grinding plate for attrition mills and disk hullers comprising a body dressed on its face and composed of a hard steel casting which alone is too brittle to preclude fracture under the stresses to which such plates are subjected in service, and a reinforcement about which said body is cast and intimately united therewith, said reinforcement being operative to maintain fragments, broken from the plate, in working position 75 during operation.

9. An attrition mill plate comprising a body composed of a hard steel casting of insufficient resistance alone to preclude fracture under the stresses to which such plates are subjected in service and having a ribbed working face, and a tough steel reinforcement about which said body is cast and with which it is intimately united, said reinforcement lying in a plane behind said ribbed working face and being operative to sustain stresses to which the plate is subjected while in operation to maintain fragments of a fractured plate in working relation during 90 95 operation.

In testimony whereof I have hereunto set my hand.

ORLANDO SHEPPARD, Jr.
